UNITED STATES PATENT OFFICE

ERNST MEIER, OF BRUNSWICK, GERMANY. ASSIGNOR TO BRAUNSCHWEIGER HÜTTENWERK G. M. B. H., OF BRUNSWICK, GERMANY

APPARATUS FOR MECHANICALLY COMBINING METALLIC AND NONMETALLIC MATTER

Application filed June 27, 1927, Serial No. 201,816, and in Germany July 2, 1926.

My invention relates to improvements in the method of and apparatus for mechanically combining metallic and non-metallic matter.

As is known to those skilled in the art, the coefficient of friction of metals is improved by mechanically combining non-metallic matter therewith. For example, for adding graphite to alloys containing aluminum and zinc or Babbitt metal a complicated operation is necessary, because a homogeneous product capable of being cast is obtained only by frequently breaking and pressing the mixed materials, the said materials being mixed either in a cold state and pressed in a hot state, or being mixed in a semi-fluid state of the metal. The object of the improvements is to provide a method by means of which a homogeneous mixture of the said materials can be obtained in a comparatively simple way, the homogeneous product being obtained by a single operation and without much mechanical work and without applying high pressure to the materials. With this object in view my invention consists in first melting the metal, such as aluminum or alloy, into a liquid state and adding thereto the foreign matter, such as graphite in vacuo. I have found that thereby the parts are intimately mixed with each other, and oxidation is prevented, the amount of oxygen being comparatively small by reason of the operation in vacuo.

In order that my invention be more clearly understood an apparatus suitable for putting the same into effect has been shown in the accompanying drawing, in which the same reference characters have been used in all the views to indicate corresponding parts. In said drawing,

Fig. 1 is a sectional elevation showing the apparatus, and

Fig. 2 is a detail sectional view taken on the line 2—2 of Fig. 1 and showing the wings for stirring the materials being mixed.

In the practice of the invention I first melt the metal or alloy into a very fluent state, I introduce the same into a vacuum chamber, and I add the foreign matter such as graphite while stirring the materials in vacuo.

In the example shown in the figures the apparatus used for carrying out my improved method consists of a furnace having a vertical cylindrical wall *a* formed at its bottom with an opening *b*. Through the said opening a nozzle *c* for supplying liquid fuel is passed into the furnace below a bridge *d*, the hot gases produced by combustion of the liquid fuel escaping through a tubular outlet *e* connected with a stack. At the top of the said furnace there is a semi-spherical container *f*, which is formed at its bottom with a tubular outlet *g* passed through the wall *a* of the furnace and adapted to be closed more or less by means of a plug *h* made integral with a screw-threaded spindle *h*¹ screwing in an extension *g*¹ of the outlet *g* and carrying a hand wheel *h*². On the top face of the container *f* a semi-spherical cap *i* is placed which is similar in dimension to the container *f*, and which is provided at its top with a tubular intake member *q* the top part *s* of which is adapted to be closed by a lid *t*, and which is formed with a lateral branch *r* adapted to be connected to a vacuum apparatus. The cap *i* carries two arms *k* projecting laterally therefrom and providing bearings for a rotary shaft *l* extending through the spherical chamber provided by the container *f* and the cap *i*, a suitable packing medium *n* being provided for closing the said chamber in an air-tight manner. The shaft *l* is adapted to be rotated by means of pulleys *m* keyed thereto. Within the said chamber *f*, *i* two pairs of arms *o* are fixed to the shaft *l*, and to each pair of arms a substantially semi-circular foraminated plate *p* is fixed. In the operation of the apparatus the materials to be combined, for example aluminum and powdered graphite, are fed into the container *f* through the intake member *q*, whereupon the said member *q* is closed by means of the lid *t* and the air is removed through the branch *r*. After having produced the desired vacuum liquid fuel is supplied through the nozzle *c*, so that the metal contained within the chamber *f*, *i* is melted, and the shaft *l* is rotated for stirring the molten metal and graphite, the vacuum being maintained while thus stirring the contents of the container.

Thereby the amount of oxygen within the container *f*, *i* is small, and any gases produced within the said container are immediately removed.

5 After the materials have been sufficiently stirred they are tapped off by removing the plug *h* and cast into the form of bars. I have found that the material thus produced is perfectly homogeneous, that it can be cast, 10 and that the components are not separated by remelting or otherwise working the same. By adding graphite to metals or alloys to be used in bearings a material is obtained which is valuable by reason of its low coefficient of friction.

15 I claim:

1. An apparatus for combining metallic and non-metallic matter comprising a stationary container having inlet and outlet 20 passages, means for tightly closing said passages, means for producing a vacuum in the container, means for supplying heat to liquefy contents of the container, and rotary stirring means in the container.

25 2. A furnace for combining metallic and non-metallic matter comprising a container, a removable cover therefor, power-driven means carried by said cover for agitating the contents of the container, said means 30 being removable with said cover, and means for heating the contents of the container to a temperature sufficient to melt the metallic contents.

35 3. A furnace for combining metallic and non-metallic matter comprising a container, a removable cover therefor, laterally extending arms on said cover, bearings on said arms, a shaft rotatable in said bearings, a pulley for rotating said shaft, foraminous 40 beater plates carried by said shaft within said container, and means for heating the container to fuse its metallic contents.

45 4. In a furnace for combining metallic and non-metallic materials, a container, means for heating the same to fuse its metallic contents, a shaft extending horizontally of the container, and foraminous beating plates on said shaft.

50 In testimony whereof I have hereunto set my hand.

ERNST MEIER.
